SAND TRAP

William H. White, Roanoke, Va., assignor to
Morris B. Brewster Co., Inc., Chicago, Ill.

Application March 17, 1947, Serial No. 735,161

4 Claims. (Cl. 291—11)

1

The invention relates to sand traps for delivering sand under air pressure, to railway rails.

Sand traps now in use, are equipped for delivering an initial clean-out blast of sand to the delivery pipe, for clearing it of any accumulation, and continued air pressure to the trap, for discharging sand to the rails. In one type of sanding equipment, the sand trap is manually controlled by a valve in the locomotive cab, with separate pipe connections between the trap and said valve, for delivering air to the sand delivery nozzle and to the clean-out duct, respectively. In another type of sanding equipment, the valve controlled by the engineer, is connected to the sand trap through a remote control valve, separate from and outside of, the casing of the trap, which controls the air for the clean-out blast and the air delivered to the sand discharge nozzle.

One object of the invention is to provide a sand trap with a casing which has a passage internally formed therein and a valve in said passage for automatically controlling the clean-out blast, and which embodies the nozzle for discharging the sand from the trap, to both of which air is directly delivered by a single pipe from the engineer's control valve. In the attainment of this object, a single pipe delivers air from the engineer's control valve to the casing of the sand trap, for the clean-out blast and the nozzle in the trap, so that a remote control valve separate from and outside of, the casing of the trap, is eliminated.

Another object of the invention is to provide a sand trap which includes a valve for automatically controlling the clean-out blast, which is simple in construction and efficient in operation.

Other objects of the invention will appear from the detailed description.

The invention consists in the several novel features hereinafter set forth, and more particularly defined by claims at the conclusion hereof.

In the drawings:

Fig. 1 is a vertical longitudinal section of a sand trap embodying the invention.

Fig. 2 is a section taken on line 2—2 of Fig. 5.

Fig. 3 is a detail of the valve seat for the automatic valve for the clean-out blast.

Fig. 4 is a section taken on line 4—4 of Fig. 1.

Fig. 5 is a longitudinal section illustrating a modified form of the invention.

The invention is exemplified in a sand trap which comprises a single casing generally designated 10. This casing is formed with an inlet leg 11 for the sand, and a horizontally extending

2

leg connecting an inlet leg 12 and an inclined discharge leg 13. A pipe 14 for delivering sand to the rails, is communicatively connected to the discharge leg 13. An air nozzle 15 is screw-threaded into a wall of the casing 10, at one side of the lower portion of leg 11, for directing air into horizontal leg 12, and discharging sand through leg 13 into the delivery pipe 14. Nozzle 15 is screw-threaded to a socket 16 in casing 10, for adjustment to vary the rate of discharge of the sand from the trap.

Air is delivered to the trap, through a pipe 18, which is connected to the engineer's control valve in the locomotive cab and is connected to casing 10, by a fitting or coupling 19. A vertical duct 20 is integrally formed in the casing and is communicatively connected to receive air from fitting 19 and pipe 18. Duct 20 receives air for delivery to the nozzle 15, for discharging sand, and also for delivery to the clean-out duct hereinafter described. A plug or head 21 is screw-threaded into the wall of the casing at the outer side of duct 20, in axial alignment with nozzle 15, and seats against the wall at the inner side of said duct. Head 21 is provided with one or more radial ports 22, which communicatively connect duct 20 and a socket 23 in said head, for delivering air into the bore of nozzle 15 and impelling the sand through legs 12 and 13, into delivery pipe 14. A plug 24 is screw-threaded into the lower wall of casing 10 below leg 11, for access to said leg, for dislodging any sand which may become packed in the trap. Air for the clean-out blast is delivered from the upper end of vertical duct 20, which is in direct communication with the pipe 18 from the engineer's control valve, via a semi-annular duct 28, which extends around one side of the inlet leg 11 of the casing, a longitudinally extending or elongated valve chamber or passage 27 which leads from duct 28, and an automatic valve which controls the flow of air to a chamber 34 adjacent one end of the casing 10, to a duct or nozzle 26, which discharges air into the delivery pipe 14. Duct 28, valve chamber 27, chamber 34 and duct 26, are internally and integrally formed in the casing 10, so that the air for the clean-out blasts will be delivered from pipe 18, through casing 10, to the clean-out discharge duct. The valve for automatically controlling the clean-out blast, is of the delayed action type, for predeterminedly limiting the duration of the clean-out blasts, and is embodied in the casing 10. This valve comprises a concave seat 30 on the inner face of a plug 31 which is screw-threaded in the

casing at the front end of chamber 27 and a ball 32 adapted to close against said seat and move or roll longitudinally in the chamber 27. Ball 32 is of lesser diameter than the chamber 27, to permit air to pass around the ball and retard its closing against seat 30 by air under pressure, and is of sufficient weight to retard its movement by air pressure and to gravitate from seat 30, and roll rearwardly in chamber 27 when there is no air pressure in chamber 27. The seat 30 is positioned so that the ball 32 will be lifted slightly by air pressure to retard its movement to the fully closed position. When air under pressure from duct 20, passes into chamber 27 upon initiation of a sanding operation, ball 32 will be retarded in its movement toward seat 30, sufficiently to cause a clean-out blast to pass through the duct 26 into the delivery pipe 14. In this manner, the delay in the seating of the ball, automatically controls the duration of the clean-out blasts. In some instances, it is desirable to permit a small volume of air to pass through the clean-out duct 26 during the entire sanding operation. When this is desired, a fine port 37 may be formed through the plug 31. This also prevents unseating of ball 32 in the event of any back pressure in duct 26 during the sanding operation.

The operation of the trap will be as follows:

For a sanding operation of the rails, the engineer will operate the control valve in the cab, to supply compressed air through pipe 18, to the duct 20. Normally, ball 32 will be positioned in chamber 27, some distance from the valve seat 30. When the compressed air reaches the duct 20, air will flow through ports 22, socket 23, and nozzle 15, into the leg 12, and discharge sand from the trap into delivery pipe 14. Simultaneously, air will flow via duct 28, into valve chamber 27. When air enters chamber 27, some air will flow around ball 32 and will exert some pressure against ball 32, which is of lesser diameter than chamber 27. The lift necessary to seat the ball and the weight of the ball, will delay the engagement of ball 32 with its seat 30. During this period of delay, air from chamber 27 will pass through the bore of plug 31, into chamber 34, from which it passes through clean-out duct 26, into the delivery pipe, for the desired momentary or pre-determined, short clean-out blast to pipe 14. When the ball 32 closes the valve, the clean-out blast will be automatically discontinued during the remainder of the period during which the engineer may selectively control the delivery of air through nozzle 15, for the delivery of sand to the rails. When air is cut off at the engineer's valve to the sand trap, at the conclusion of a sanding operation, the ball 32 will gravitate away from seat 30. The residual exhaust of air and sand through leg 12 and delivery pipe 14, will produce a degree of suction in duct 20 and passage 28, which will cause ball 32 to move farther away from seat 30, so that the ball will be positioned a considerable distance from seat 30, when the next sanding operation is initiated. As a result, at the commencement of the next succeeding sanding operation, the ball 32 will be positioned away from seat 30, to delay its closing, for automatically controlling the duration of the clean-out blast. In practice, the weight of the ball and the relative diameters of the chamber 27 and the ball, may be varied to vary the delay in the closing of the seat.

In Fig. 5, the invention is exemplified in a trap which is connected to deliver sand to the rails,

through a sand delivery pipe 14a, which leads horizontally away from the leg 12 of the casing. In this form of the invention, the automatic valve for controlling the clean-out, embodies elements similar to those described. Casing 10a is provided with a leg 12a, which leads directly from the nozzle to the pipe 14a. A clean-out nozzle or duct is formed in the casing, to direct air into pipe 14a. A plug 35a is screw-threaded into said casing at the outer end of a chamber 27a which is communicatively connected to the duct 28, as before described. Plug 30a is provided with a seat for a ball 32a which is adapted to roll in chamber 27a. Chamber 34a, into which the air

15 passes for the clean-out blast from the bore of plug 30a, is connected to duct 26a, which directs air forwardly into the bore of delivery pipe 14a. The operation of the automatic ball valve is substantially as before described. If desired, the 20 bottom of passage 27a may be inclined downwardly away from plug 30a to cause the ball to roll away from seat 30a, as illustrated in Fig. 5.

The invention exemplifies a sand trap with a ball valve which is embodied in the casing of the sand trap, and automatically controls the duration of the clean-out blasts and which receives compressed air from an inlet duct formed in the casing from a single pipe which is controlled at the engineer's valve, and dispenses with 25 a remote control valve outside of the casing.

The invention is not to be understood as limited to the details described, since these may be modified within the scope of the appended claims without departing from the spirit or scope of the 30 invention.

Having thus described the invention, what I claim as new and desire to secure by Letters Patent is:

1. In track sanding apparatus, a sand trap, 40 comprising: a casing having embodied therein inlet and discharge legs for sand, a duct for delivering a clean-out blast to the discharge leg, and an elongated valve chamber; an air nozzle in the casing for discharging sand therefrom; a 45 single connection for delivering air into the casing from an engineer's control valve; means in the casing for conducting air from said connection to the nozzle and to said chamber; and a valve for automatically controlling a clean-out 50 blast, disposed in the trap casing, and including a seat, and a valve member in said chamber normally spaced from said seat adapted for retarded movement by air from said connection to said seat, and to deliver a clean-out blast of 55 limited duration to the clean-out duct during said retarded movement, and movable by gravity away from the seat when the supply of air to the connection is cut off.

2. In track sanding apparatus, a sand trap 60 comprising: a casing having embodied therein inlet and discharge legs for sand, a duct for delivering a clean-out blast to the discharge leg and an elongated valve chamber extending longitudinally of the connecting leg; an air-nozzle 65 in the casing for discharging sand therefrom; a single connection for delivering air directly into the casing from an engineer's control valve; means in the trap casing for conducting air from said connection to the nozzle; a duct in the casing 70 for conducting air from said connection to said chamber; and a valve for automatically controlling a clean-out blast, including a seat at one end of the chamber and a ball in, and of lesser diameter than, said chamber, and adapted 75 for retarded movement to the seat by air from

said connection to deliver a clean-out blast of limited duration to the clean-out duct during said retarded movement and movable by gravity away from the seat when air to the connection is cut off.

3. In track sanding apparatus, a sand trap comprising: a casing having embodied therein inlet and discharge legs for sand, a duct for delivering a clean-out blast to the discharge leg and an elongated valve chamber extending longitudinally of the connecting leg; an air nozzle in the casing for discharging sand therefrom; a single connection for delivering air directly into the casing from an engineer's control valve; means in the trap casing for conducting air from said connection to the nozzle; a duct in the casing for conducting air from said connection to said chamber and extending around the inlet leg; and a valve for automatically controlling a clean-out blast including a seat at one end of the chamber and a ball in, and of lesser diameter than, said chamber, and adapted for retarded movement to the seat by air from said connection to deliver a clean-out blast of limited duration to the clean-out duct during said retarded movement and movable by gravity away from the seat when air to the connection is cut off.

4. In track sanding apparatus, a sand trap comprising: a casing having embodied therein inlet and discharge legs for sand, a duct for delivering a clean-out blast to the discharge leg and an elongated valve chamber extending longitudinally of the connecting leg; an air nozzle in the casing for discharging sand therefrom; a single connection for delivering air directly into the casing from an engineer's control valve; means in the trap casing for conducting air from said connection to the nozzle; a duct in the casing for conducting air from said connection to said chamber and extending around the inlet leg; and a valve for automatically controlling a clean-out blast including a seat at one end of the chamber and a ball in, and of lesser diameter than, said chamber, and adapted for retarded movement to the seat by air from said connection to deliver a clean-out blast of limited duration to the clean-out duct during said retarded movement and movable by gravity away from the seat when air to the connection is cut off.

20
25

30

dinally of the connecting leg; an air nozzle in the casing for discharging sand therefrom; a single connection for delivering air directly into the casing from an engineer's control valve; means in the trap casing for conducting air from said connection to the nozzle; a duct in the casing for conducting air from said connection to said chamber and extending around the inlet leg; and a valve for automatically controlling a clean-out blast, including a plug at one end of the chamber provided with a seat and a ball in, and of lesser diameter than, said chamber, and adapted for retarded movement to the seat by air from said connection to deliver a clean-out blast of limited duration to the clean-out duct during said retarded movement and movable by gravity away from the seat when air to the connection is cut off.
